Patented Dec. 22, 1964

199,872

FILM TRANSPARENCY CUTTER-TACKER

Frederick G. Knowles, Rochester, N.Y., assignor to Eastman Kodak Company, Rochester, N.Y., a corporation of New Jersey

Filed June 29, 1964, Ser. No. 80,633

Term of patent 14 years

(Cl. D61—1)

FIG. 1

Des. 199,872

PAGE 2

FIG. 2

Des. 199,872

PAGE 3

FIG. 3

FIG. 4

FIG. 1 is a top plan view of a film transparency cutter-tacker showing my new design;

FIG. 2 is a right-side elevational view thereof;

FIG. 3 is a left-side elevational view thereof;

FIG. 4 is a front elevational view thereof; and

FIG. 5 is a rear elevational view thereof.

I claim:

The ornamental design for a film transparency cutter-tacker, as shown.
